UNITED STATES PATENT OFFICE.

DOURA C. PUTNAM, OF LYONS, NEW YORK.

PROPELLING MECHANISM FOR BOATS.

SPECIFICATION forming part of Letters Patent No. 718,156, dated January 13, 1903.

Application filed February 19, 1901. Serial No. 47,990. (No model.)

To all whom it may concern:

Be it known that I, DOURA C. PUTNAM, of Lyons, in the county of Wayne, in the State of New York, have invented new and useful 5 Improvements in Propelling Mechanism for Boats, of which the following, taken in connection with the accompanying drawings, is a full, clear, and exact description.

My invention relates to improvements in 10 propelling mechanism for boats, the objects being to provide a simple and compact propelling device by which the operator is permitted to face in the direction of movement of the boat and to vary the reach and depth 15 of stroke of the oar and in which the oars may be readily folded and rocked inwardly into the boat when not in use.

The further object of my invention is to provide means whereby the oar and its rocking 20 frame may be readily removed or placed in position when desired. To this end the invention consists in the combination, construction, and arrangement of the parts of a propelling mechanism for boats, as hereinafter 25 fully described, and pointed out in the claims.

Referring to the drawings, Figure 1 is a top plan of one side of a boat and my invention applied thereto. Fig. 2 is an enlarged perspective view of the device seen in Fig. 1, the 30 free ends of the oar-sections being broken away. Fig. 3 is an end view of the parts seen in Fig. 2, the oar-sections being folded and rocked inwardly into the boat. Fig. 4 is a detail end view of the base-plate and rocking 35 support, showing the manner of assembling the same, the trunnion being shown in section. Fig. 5 is a perspective view of one of the outer oar-sections.

Similar reference characters indicate corresponding parts in all the views.

This invention consists, essentially, of a base-plate A, a rocking support B, intermeshing gears C, and oar-sections c and c'. The base-plate A may be of any desired form or 45 material, is preferably secured to one of the side rails d of a boat D, a portion of which is seen in the drawings, and usually consists of a lengthwise bar a, adapted to rest upon the upper face of the rails d, and is provided with 50 depending ears a', engaged with the outer face of said rail. The upper bars a and ears a' are provided with suitable apertures for

receiving screws or other suitable fastening means 1, which serve to firmly hold said base-plate in position. This base-plate is provided 55 with upwardly-projecting ears or lugs 2, each of which is formed with a slot 3, extending downwardly from its upper end face, the lower ends of said slot being enlarged at 4 and forming a suitable bearing for the rocking support B, presently described. The support B may also be of any desired form or material and preferably consists of an open frame having upper and lower walls b and end walls b', the upper and lower walls being provided with bearings 5, aligned with each other vertically and arranged one in advance of the other lengthwise of the boat D or rail d. The end walls b' are provided with trunnions 6, projecting from their lower ends, are movable into and out of the slots 3, and are provided with annular end shoulders 7, adapted to engage the outer faces of the upwardly-projecting ears 2. These trunnions 6 are formed of substantially the same diameters as the 75 enlarged lower ends of the slots 3 and are usually provided with cut-outs or flattened portions 8 in their peripheral faces for permitting the insertion of the trunnions into the reduced upper ends of the slots 3. The lower 80 end of each of these slots is circular in form for forming a bearing for the adjacent trunnion, one of the side walls of the slot being substantially coincident with the inner wall of the circular portion of the slot, and the upper end of the other wall of said slot usually extends inwardly beyond the outer wall of the bearing 4. The cut-out or flattened portion 8 of each of the trunnions 6 is preferably disposed in a plane at an angle with the end 85 walls b', and when it is desired to insert the trunnions into the slots 3 the rocking frame B is tilted in such position that the flattened surface 8 is substantially coincident with the inner wall of said slot. The rocking frame B 90 is then lowered until the trunnions 6 are engaged with the bearings 4, whereupon the frame B is rocked to its upright position and is securely held from displacement by the overlapping portion of the outer walls of the 100 slot. In like manner when desired to remove the supporting-frame said frame is rocked on the trunnion 6 until the face 8 is substantially parallel with the inner wall of

the slot, whereupon the rocking support may be readily moved upwardly out of the bearing 4.

The gears C are supported between the upper and lower walls b, and the end walls b' are provided with suitable hubs 10, having reduced portions 11 journaled in the bearings 5, or said hub may consist of a hollow tube and the reduced portions 11 may consist of a shaft or spindle having its opposite ends riveted or otherwise secured to the upper and lower walls b. In this event the gears C would be journaled upon said shafts or spindles. These gears C may be of any desired size and are each provided with an angular bracket 12 for receiving the oar-sections c and c'. These brackets are generally arranged one in advance of the other lengthwise of the boat or rail d at one side of the axes of their respective gears C when the oar-sections are parallel with each other. As seen in the drawings, these brackets 12 are arranged transversely across the upper faces of their respective gears in advance of their axes and form chords of their respective gears, or, in other words, are arranged substantially tangential with relation to the axes of said gears and at an angle with their radii.

The adjacent ends of the oar-sections c and c' extend transversely across the upper face of the gears C and are secured to their respective brackets 12 by suitable fastening means, as screws or bolts 13, said bolts or screws being passed through apertures formed in the brackets and the adjacent ends of the oar-sections, which apertures are arranged at substantially right angles to each other for permitting the insertion of the vertical and horizontal bolts or screws. The oar-section c preferably forms the hand-engaging portion of the oar. The oar-section c' extends outwardly from its bracket 12, is adapted to dip into the water, and usually consists of a single piece of suitable material, as wood, formed with a lengthwise slot 14, extending inwardly from its outer end face, and a flat piece E of suitable material, such as sheet metal, which is inserted in said slot, is formed of greater width than the adjacent portion of the oar-section c' and is secured in position by suitable rivets or other fastening means 15.

It is evident from the foregoing description that the operator is always facing the direction of movement of the boat and that when the oars are not in use it is simply necessary to move the hand-engaging section of the oar rearwardly to the limit of its movement, thereby folding the water-engaging oar-section rearwardly at the outer side of the oar-section c and substantially parallel therewith, whereupon the rocking support B may be rocked inwardly and the combined weight of the oars and gears secured thereto, and also the weight of the upper portion of the supporting-frame tends to hold the rocking frame and parts carried thereby within the

boat. When it is desired to remove the rocking support and the gears and oar-sections mounted thereon, it is only necessary to register the flattened portions of the trunnions 70 with the inner side walls of the slots and then to lift the whole device bodily from said slots and deposit the same in the boat-house or other secure place, if desired.

The operation of my invention will now be 75 readily understood upon reference to the foregoing description and the accompanying drawings, and it will be noted that the same change may be made in the detail construction and arrangement of the component parts 80 of the device seen in the drawings without departing from the spirit of this invention.

Having thus described my invention, what I claim, and desire to secure by Letters Patent, is—

1. A propelling mechanism for boats comprising a support, intermeshing gears journaled on the support and provided with angular brackets disposed at the same side of their respective axes when the brackets are 90 in their operative position, and oar-sections having their adjacent ends secured to said brackets.

2. A propelling mechanism for boats comprising a rocking support, and two gear-connected oar-sections journaled on the support and arranged at the same side of their respective axes, when the oars are extended so as to fold on opposite sides of their axes.

3. A propelling mechanism for boats comprising a rocking support consisting of an elongated open frame having bearings arranged one in advance of the other, and gear-connected oar-sections journaled in said bearings and adapted to fold parallel with a line 105 drawn through said bearings.

4. A propelling mechanism for boats comprising open-sided bearings secured to the side rail of the boat one in advance of the other, a rocking support removably mounted 110 in the bearings and having upper and lower walls, gears journaled on the support between said walls one in advance of the other lengthwise of the boat, and oar-sections secured to the gears at the same sides of their pivots 115 when the oars are extended.

5. The combination with the side rail of a boat, a base-plate secured to the rail and provided with upwardly-projecting ears having slots extending downwardly from their upper 120 end faces, said slots being enlarged at their lower ends, and an open frame having end walls provided with trunnions movable into and out of said slots and provided with flattened portions, intermeshing gears journaled in the frame, and oar-sections secured to the gears at the same side of their axes when the oars are extended so as to fold on opposite sides of their axes, for the purpose specified.

6. The combination with the side rail of a boat, a base-plate secured to the rail and pro-

vided with upwardly-projecting ears having slots extending downwardly from their upper end faces, said slots being enlarged at their lower ends, and a rocking support having trunnions movable into and out of said slots and provided with flattened portions for the purpose specified, and gear-connected oar-sections journaled on the rocking sup-

port one in advance of the other for the purpose set forth. 10

In witness whereof I have hereunto set my hand this 15th day of December, 1900.

DOURA C. PUTNAM.
